[57] **CLAIM**

I claim the ornamental design for tool container, as shown.

DESCRIPTION

FIG. 1 is a perspective view of a first embodiment of the design;
FIG. 2 is a top view of the first embodiment;
FIG. 3 is a front view of the first embodiment;
FIG. 4 is a left side view of the first embodiment;
FIG. 5 is a right side view of the first embodiment;
FIG. 6 is a bottom view of the first embodiment;
FIG. 7 is a bottom view of a second modified embodiment;
FIG. 8 is a rear view of the first embodiment;
FIG. 9 is a perspective view of a third modified embodiment of the design;
FIG. 10 is a top view of the third modified embodiment;
FIG. 11 is a front view of the third modified embodiment;
FIG. 12 is a left side view of the third modified embodiment;
FIG. 13 is a right side view of the third modified embodiment;
FIG. 14 is a bottom view of the third modified embodiment;
FIG. 15 is a rear view of the third modified embodiment;
FIG. 16 is a perspective view of a fourth modified embodiment of the design;
FIG. 17 is a top view of the fourth modified embodiment;
FIG. 18 is a front view of the fourth modified embodiment;
FIG. 19 is a left side view of the fourth modified embodiment;
FIG. 20 is a right side view of the fourth modified embodiment;
FIG. 21 is a bottom view of the fourth modified embodiment; and,
FIG. 22 is a rear view of the fourth modified embodiment.
